OVERHEAD DOOR CONSTRUCTION

David M. Robinson, New Britain, Conn., assignor
to The Stanley Works, New Britain, Conn., a
corporation of Connecticut

Application April 19, 1934, Serial No. 721,298
Renewed July 17, 1936

10 Claims. (Cl. 20—20)

This invention relates to overhead door constructions, and particularly to those constructions wherein a plurality of vertically movable doors are used to close a door opening in a building. 5
An object of the invention is to provide an improved arrangement whereby the intermediate or center post or posts, which normally serve the purpose of guiding those edges of the doors remote from the sides of the door opening, may be moved along a transverse or cross track to a position out of the doorway and to one side thereof, the arrangement being characterized by various features of novelty and advantage, and particularly by its simplicity in construction, its economy 10 in manufacture, and the ease and facility with which it may be installed.

A further aim of the invention is to provide an improved arrangement of removable posts which will not interfere with positioning the horizontal 20 portions of the door supporting tracks at any desired height, nor require any additional head room over that required if such an arrangement were not provided.

A further object resides in the provision, in an 25 overhead door construction of the character described, of means for rendering the posts easily movable from a position in which they support the edges of the doors intermediate the sides of the door opening to a position in which they are 30 clear of the door opening.

A still further object resides in the provision in an overhead door construction of the character described, of means for locking the movable posts in position to support the said edges 35 of the vertically movable doors and means for automatically holding the doors in open position whenever the posts are removed from their door supporting position.

Other objects and advantages will appear as 40 the description proceeds.

In the accompanying drawings, I have illustrated a suitable mechanical embodiment of the idea of the invention. The drawings however, are to be taken for the purpose of illustration only 45 and not as limiting the invention the scope of which is to be measured entirely by the scope of the appended claims.

In the drawings,

Fig. 1 is a rear elevational view of an overhead 50 door construction constructed according to the idea of this invention;

Fig. 2 is a vertical sectional view of one overhead door and a portion of the building in which the overhead doors are used, showing means for 55 supporting and guiding the door, and means for

supporting and guiding a movable post adapted to support the adjoining edges of two adjacent doors;

Fig. 3 is an elevational view of the locking means for the movable post; 5

Fig. 4 is a side elevational view of the locking means illustrated in Fig. 3;

Fig. 5 is a horizontal sectional view on the line 5—5 of Fig. 2 showing in plan view the movable post and the means for supporting the doors and 10 movable post;

Fig. 6 is a view of a lock device for maintaining the doors in their uppermost or open position whenever the movable post is removed from its 15 door supporting location.

Fig. 7 is an elevational view of the upper portion of the removable door post forming a part of my invention, the supporting track for the door post and the portion of the building immediately surrounding the track being shown in 20 section; and

Fig. 8 is an elevational view on an enlarged scale of the safety hook and supporting bushing therefor illustrated in Fig. 2.

Referring to the drawings in detail, the numeral 10 generally indicates one wall of a building 25 provided with a door opening, generally indicated at 12. This building may be an aircraft hangar, a garage building, or a factory building, having a door opening so wide that it would not 30 be practical to close the same by means of a single door because of the excess weight of such a door and the difficulty of effectively bracing against the strains and stresses set up in a door of such large size during its opening and closing 35 movements, and also because the opening of such a large door in cold weather spills all of the heated air out of the building and it then becomes necessary to re-heat the building every time the door is opened. It is, therefore, of great advan- 40 tage to close the door opening by means of a plurality of relatively small doors, each small door being supported and guided along each of its edges by a track member. With this arrangement, each door is movable from a vertical posi- 45 tion in which it closes a certain area of the door opening to a substantially horizontal overhead position in which each door is within the building and above the door opening, leaving the area of the door opening uncovered by the door clear. 50 With such a construction, however, it is necessary to provide posts between each two adjacent doors to support the adjoining edges of these doors intermediate the sides of the door opening, and when the doors are all raised to their open posi- 55

tion, as described above, these posts still stand in the door opening. In order to render the entire door opening free and clear, I provide an improved arrangement for moving these door supporting posts out of the door opening.

In order to guide and support the door in its two operative positions and in its movements between these two positions, there is a track at each edge of each door, these tracks, such as 18, 19, and 20, each being provided with a vertical section, a horizontal section, and a curved intermediate section, the vertical, horizontal, and curved sections of each track being indicated at 22, 23, and 24 in Fig. 2. The vertical section of each side track, such as track 18, is secured to the wall of the building by means of suitable track brackets 27. The curved section and the forward end of the horizontal section of each side track is secured to the building by means of a supporting plate, such as the plate 29, of substantially triangular shape and having an apertured flange 30 along one edge thereof secured to the building by suitable bolts or screws.

The numeral 25 designates a removable post positioned in the door opening between the adjacent edges of the doors remote from the side edges of the door opening, there being shown but one such post but it being understood that more than one may be provided. The vertical portions of the center tracks 19 and 20 are carried on the opposite sides of this post. Above each post is a plate 29' provided with a flange 30' for securing the same to the building above the door opening. This plate carries, upon opposite sides thereof, the curved portions of the tracks 19 and 20.

The doors (one of which is indicated at 35) in the construction illustrated, are of the type known as articulated doors; that is, each door is made up of a plurality of horizontal sections hinged together along their adjoining edges. Each hinge 40 carries a roller 41 adapted to engage in the associated track for the purpose of supporting and guiding the door in its opening and closing movements. At the upper end of the door, a roller 42 is secured to each side of the door by means of a hinged radius arm 43, the lower ends of these arms being pivotally secured to the door by hinge connections 44. These radius arms are bent so that the upper section of the door rests upon them whenever the door is raised or partly raised. A short track member, as indicated at 45, of channel section, is secured to each end plate 29 and to each side of each intermediate plate 29' substantially tangent with the middle of the respective curved sections of the track, and a guide stud 46, extending outwardly from the edge of each door near each upper corner thereof, cooperates with these short tracks to swing the upper ends of the upper sections of the doors toward the door jamb 48 when the doors are lowered and away from the door jamb 48 and along a path parallel to the upper parts of the main tracks as the doors are raised. An auxiliary plate 50 is secured to the upper portion of each of the end plates 29 and to each side of each intermediate plate 29' and each auxiliary plate carries a rotatable block or sheave 51 over which a cable 52 passes for raising and lowering the doors, one end of each cable being connected to the respective door adjacent to the bottom thereof and the other end being connected to the door counterbalancing mechanism, not illustrated. It will be understood that there is a cable 52 for each edge of each door and that there is an associated

sheave 51 for each cable and that there is a main track, a short track, and a supporting plate at each edge of each door and also that each edge of each door is provided with rollers cooperating with the associated track.

The main tracks 19 and 20 serve to support and guide the adjoining edges of two adjacent doors. The post 25, in the construction illustrated, is a steel beam of I-section having a web 53 and flanges 54 and 55. The vertical sections 22 and the lower portions of the curved sections of the tracks 19 and 20 are secured to opposite sides of the web 53 in any suitable manner. These track members are broken within the lower part of the curved section 24, as indicated by the broken line 5-5 of Fig. 2, so that the lower portion of the door track may be moved laterally with respect to the upper portion thereof. The post 25 has secured to the outer surface of the flange 54, adjacent to the top thereof, an apertured block 57 through which extends a vertically positioned bolt 58. This block and bolt form a swivel connection for supporting the upper end of the post upon a roller carriage or trolley, generally indicated at 60, which travels within a box track 61 secured to the building by means of an angle iron 62 which has one web welded or otherwise suitably secured to the track and the other web secured to bucks 72 and 73 by bolts 62'. The roller carriage has a bridge member 63 supported at each end by a pair of rollers, indicated at 64. The upper end of the bolt 58 extends downwardly through a centrally located vertical aperture in the bridge member so that its head bears upon the upper surface of the bridge member, and through the block 57, and carries upon its lower end a pair of lock nuts 65. The web 53 and flange 54 of the post are cut away at their upper ends, as particularly illustrated in Fig. 7, to provide at the front side of the post an upwardly extending projection 67 to which the block 57 is secured. This cut away portion has a vertical edge along the projection 67 and a horizontal edge extending forwardly from the flange 55, the horizontal and vertical edges being joined by a diagonal edge cut in the web 53. The lower portion of the track member 20 terminates adjacent the horizontal edge, and the short guide track member 45 is divided along the diagonal edge. This construction of the top part of the post renders it possible to locate the track 61 and carriage or hanger 60 above the end of the post and in front of the same so that the track 61 may be positioned well above the lines 55 along which the guide tracks are severed and the track 61 will not, in any way, interfere with or restrict the door opening 12. The lower forward corner of each intermediate plate 29' is cut away, as indicated at 71, so that the upper 60 end of the post may be moved past this plate.

It is desirable in a construction of this character that the door post, when in a position to support the edges of the doors, should be so located that the center tracks 19 and 20 are 65 in the same vertical plane as the fixed track 18 and also the fixed track corresponding to the track 18 at the other side of the door opening and that, when moved to clear the door opening, the post should come in behind the wall 70 of the building at the side of the door opening in such position that the portions of the track 19 on the post will nest in the track 18, as illustrated in dotted lines in Fig. 5. In order to provide for this movement of the post, it is 75

necessary to slant the post carrying track 61 relative to the wall of the building. Between the lintel 70 and the roof, the building is provided with a plurality of bucks, indicated at 72 5 and 73, and in order to locate the track in the slanted position illustrated in Fig. 5, the buck 72 is completely severed and the end of the track remote from the side of the doorway is located against the building wall within the 10 cross sectional area of this buck. The buck 73 at the side of the door opening is provided with a groove extending through only a portion of its thickness, and the end of the track at the side of the door opening is located in this 15 groove. Thus the track 61 slopes away from the building from the end thereof remote from the side of the door opening to the end thereof adjacent to the side of the door opening and, as the carriage 60 supporting the post 25 runs 20 along this track, the post will be shifted inwardly as well as laterally so that, in its limiting position, illustrated by dotted lines in Fig. 5, it will be located within the building and the door track 19 carried by the post will mesh with, 25 or nest in, the track 18 supported upon the building wall.

While the upper end of the post is supported by the construction just described, in order to provide a firm and rigid support for the intermediate edges of the doors, it is necessary that the bottom of the post should be firmly locked in position, and to this end, I have provided a locking device, particularly illustrated in Figs. 3 and 4, carried upon the rear face of the post 25. This locking device comprises a pair of vertically movable bolts or pins 75 and 76 slidably secured to the rear surface of the post 25 by means of guides 77 bolted to the inner flange 55 of the post. The lower ends of these pins 30 are tapered and are adapted to engage in suitable apertures 78 provided in a plate 80 embedded in the tread of the doorway. The pins 75 and 76 are rigidly connected together at their upper ends by a transverse bar 81 so that 35 the two pins will move up and down together. The pin 75 is provided at its upper end with an apertured extension 83 to which is pivotally secured the lower end of a double link 84 the upper end of which is pivotally secured to a 40 reversing lever 85 pivotally mounted on the rear face of the post 25 by means of a bearing pin 86 and bracket 87. A pivoted double link 88 connects the opposite end of the reversing lever 85 to a collar 89 in which the lower end 45 of a shaft or rod 90 is rotatably but non-slidably secured. The rod 90 extends upwardly along the inner or rear face of the door post and intermediate its length passes through an enlarged 50 loop bracket or guide 91 secured to the rear face of the post at a convenient height for the operation of a handle 92 which is rigidly secured to the rod 90 at a location to cooperate with the loop bracket 91. The bracket 91 is provided with a shallow indentation 93 and a deep 55 indentation or slot 94 circumferentially spaced from each other, both indentations having a width slightly greater than the width of the handle 92. From the construction so far described, it will be observed that when the rod 60 90 is moved upwardly by the handle 92, the pins 75 and 76 will be moved downwardly to engage in the apertures 78 in the plate 80. The pins may be locked in this position by rotating the handle 92 to a position in which it rests in the 65 shallow indentation 93. In order to release the 70 pins 75 and 76 from engagement in the aperture 78, the handle 92 is first lifted out of the shallow indentation 93 and rotated until it is in alignment with the deep indentation 94. The handle 75 is then forced downwardly to the bottom of this indentation, which action, through the collar 89, reversing lever 85, and links 88 and 84, raises the pins 75 and 76 out of engagement with the apertures 78. The loop bracket 91 is provided with an upper abutment 96 to limit the upward 10 movement of the handle 92 and rod 90.

The rod 90 extends upwardly above the bracket 91 to a position substantially level with the top of the flange 55 and is provided with a tapered upper end adapted to take in a bore 98 in a 15 fixed bushing 100 to secure the upper end of the door against lateral movement.

In an overhead door construction of the character described, embodying removable center posts, there is some danger that the doors may 20 be accidentally lowered when the removable posts are not in a position to properly support them, resulting in a jamming of the doors and possibly in other serious consequences. In order to avoid such a contingency, I have provided, in 25 association with the post locking means, means for locking the doors in their overhead position whenever the posts are not locked in position to receive and support the doors.

Referring to Fig. 8, it will be observed that the 30 bushing 100 is rigidly secured to the plate 29' by means of a pair of bracket plates 102 and 103. These plates 102 and 103 each have an intermediate portion thereof bent into the form of a half cylinder, as indicated at 106, and a 35 straight portion projecting from each edge of the half cylinder. One straight portion of each plate overlies a downwardly projecting portion 107 formed on the plate 29'. These straight portions are positioned on opposite sides of the 40 plate 29' and are secured to the plate 29' by suitable means, such as the rivets 108. The straight portions extending from the opposite sides of the semi-cylindrical portions of the plates 102 and 103 extend between the track 45 members 19 and 20 and are secured to the track members by suitable means, such as riveting or spot welding, thus providing a substantial and rigid bracket for the bushing 100. The plate 29' is provided with a cut-out portion 109 into 50 which the bushing and the straight portions of the plates 102 and 103, included between the tracks, extend. The bushing and the bracket formed by the plates 102 and 103 are also provided with a bevel 110 along one upper side 55 thereof in order that the bushing and bracket will clear the inner surfaces of the tracks 19 and 20. The bushing 100 is provided with a reduced portion 111 included in the semi-cylindrical portions of the plates 102 and 103 and, at 60 one end of this reduced portion, is provided with a slightly enlarged journal portion 112 upon which is mounted a latch in the form of a hook 114. At the end of the reduced portion 111, opposite the journal portion 112, the bushing 100 65 is provided with a shoulder 115 of the same diameter as the journal portion 112 which is adapted to engage with the upper edges of the semi-cylindrical portions of the plates 102 and 103 to support the bushing in these plates. This 70 shoulder 115 is made of the same diameter as the journal portion 112 so that the hook 114 may be inserted upon the bushing over the end on which the shoulder 115 is formed. At the 75 opposite side of the journal portion from the

reduced portion 111, the bushing is provided with an enlarged portion or radial shoulder 111 for retaining the hook 114 on the bushing.

Referring to Fig. 6, it will be observed that the hook 114 has a loop or bearing portion 119 rotatably mounted upon the journal 112 and has a stem 120 and a bent over end portion 122 and that the track members 19 and 20 are provided with aligned apertures 124 through which the bent over portion 122 of the hook projects when the hook is in the operative position illustrated by full and dotted lines in Fig. 6. As this hook is located below the lower edges of the doors when the doors are in their uppermost or overhead position, it will be observed that, when the hook is in the operative position illustrated by full and dotted lines in Fig. 6, the bent over portion 122 of the hook blocks the tracks 19 and 20 so that the doors cannot be lowered while the hook is in this position. When it is desired to lower the doors, the hook must be swung to its second or inoperative position, indicated by broken lines in Fig. 6. To this end, the loop portion 119 of the hook is provided with a key-way or indentation 125 adapted to cooperate with a key 127 rigidly secured upon the upper end of the locking bar or rod 90. This key has a base portion 128 which surrounds the upper end of the rod and extends radially outwardly therefrom and carries, at its outer end, an upwardly extending key member 129 adapted to engage in the key-way 125 to rotate the hook 114 upon rotation of the post locking handle 92. From this description, it will be seen that, when the handle 92 is in the shallow depression 93, the key 129 will be in engagement in the key-way 125, and the hook 114 will be in its inoperative position. If the handle 92 is now lifted from the shallow depression and turned through the arc necessary to bring it into alignment with the deep depression 94, the key 129 will swing the hook 114 to the operative position illustrated by full lines in Fig. 6. When the handle is now depressed in the deep slot 94 to release the pins 75 and 76, the key 129 will be released from the key-way 125, the upper end of the rod 90 will be moved out of the bore 98, and the post may be moved. While the hook is in this position, the doors cannot be lowered. When the post is replaced in door supporting position, the doors cannot be lowered until the post has been definitely locked in position by the proper operation of the handle 92. Thus, when the handle 92 is raised to bring the same out of the deep slot 94, the key 129 is engaged in the key-way 125 but before the doors can be lowered, the handle must be swung through the arc necessary to bring it into alignment with the shallow slot 93. This movement locks the pins 75 and 76 in engagement in the apertures 78 in the plate 80 and, at the same time, swings the hook 114 to the position indicated by broken lines in Fig. 6. With the post locked and the hook in the position indicated, the doors may now be lowered to close the door openings.

The hook 114 is provided in the bent over portion 122 thereof with a safety catch 130 in the form of a spring pressed pawl adapted to engage with one side of the aperture 124 to retain the hook against accidental movement from the operative position illustrated in full lines in Fig. 6.

From the above description, it will be observed that the transverse track 61 upon which the door supporting roller trolley 60 runs may be posi-

tioned in front of the curve of the main door tracks and the movable post 25 is secured at its front face to the trolley 60. This construction, besides providing for easier operation of the movable post and for the complete removal of the post from the door opening, also provides an improved construction in which neither the movable post nor its supporting means interferes in any way with the head room beneath the overhead position of the doors. With this improved construction, the horizontal portions of the door supporting tracks may be located at any desired height and, if desired, may be positioned very close to the ceiling or roof of the building, and the door openings may be relatively high in proportion to the height of the building. Thus, with my improved door construction, an object substantially as high as the door opening may be moved through the doorway into the building without interference with any part of the door supporting structure, and it is not necessary to go to the expense of projecting the building to a great height above the height of the door opening.

While I have described and illustrated a particular mechanical embodiment of the idea of my invention, it is to be understood that the invention is not specifically limited to the construction so illustrated and described but that such changes in the size, shape, and arrangement of parts may be resorted to as to come within the scope of the appended claims.

Having now described my invention so that others skilled in the art may clearly understand the same, what I desire to secure by Letters Patent is as follows:

1. In an overhead door construction, a plurality of doors adapted to be located within a building and to close a door opening thereof, a pair of tracks for each door for supporting and guiding the same from a vertical closed position to a substantially horizontal overhead position, each of said tracks having a vertical portion, a horizontal portion and a curved connecting portion; a removable post for supporting the vertical portions of two adjacent intermediate door tracks and movable from an operative position within the door opening to a position at one side of the door opening and within the building, a cross track within the building and above the door opening and located forwardly of said curved connecting portions of said tracks, and a traveling carrier supported by said track and from which said post is suspended for movement from the door opening to one side thereof and within the building. 55

2. In an overhead door construction, a plurality of doors within the building adapted to close a door opening thereof, a pair of tracks for each door for supporting and guiding the same from a vertical closed position to a substantially horizontal overhead position within the building, a removable post normally within the door opening between the adjacent edges of the doors, said post carrying the vertical portions of the tracks for supporting said adjacent edges of the doors, 65 a cross track within the building and above and generally parallel to the door opening, a traveling hanger supported by said track and from which said post is suspended, manually operable means for locking said post in door supporting position, 70 and a locking device actuated by said manually operable means which prevents closure of the door when the post is unlocked from door guiding position.

3. In an overhead door construction, a plu- 75

- 5 rality of doors adapted to be located within a building and to close the door opening thereof, a pair of tracks for each door for supporting and guiding the same from a vertical closed position to a substantially horizontal overhead position, each of said tracks having a vertical portion, a horizontal portion, and a curved connecting portion; a removable post for supporting the vertical portions of two adjacent intermediate door tracks, 10 a cross track within the building above the door opening and located forwardly of said curved connecting portions of said tracks, and a traveling hanger supported by said cross track and from which said post is suspended.
- 15 4. In an overhead door construction, a plurality of doors positioned within a building side by side in closed position and adapted to close a door opening thereof, a removable post within said door opening and between said doors, a pair 20 or tracks for supporting and guiding the adjacent edges of said doors from a vertical closed position to a substantially horizontal overhead position; each of said tracks having a vertical portion, an overhead horizontal portion, and a 25 curved connecting portion; said tracks being broken adjacent the lower ends of said curved portions, the portions of the tracks below the break being carried by said post and the portions of the tracks above the break being fixed, a cross 30 track within the building above the door opening and forwardly of said curved portions of said door tracks, and a carriage supported by said cross track and from which said post is suspended.
- 35 5. In combination with a building having a door opening therein, a plurality of doors within said building for closing said opening, a pair of tracks for each door for supporting and guiding the same from a vertical closed position to a substantially horizontal overhead position, each of 40 said tracks having a vertical portion, a horizontal portion, and a curved connecting portion; a removable post for supporting the vertical portions of two adjacent intermediate door tracks, a cross track within said building above the door opening 45 and located forwardly of said curved connecting portions of said tracks, and a traveling hanger supported by said cross track and from which said post is suspended, said cross track being inclined inwardly at an angle to the wall of said 50 building.
- 55 6. In combination with a building having a door opening therein, an overhead door construction for closing said door opening comprising, a plurality of overhead doors within said building movable between a vertical position and a substantially horizontal overhead position, a pair of tracks for supporting and guiding each door, each of said tracks comprising a horizontal overhead portion and a vertical portion, a removable 60 post for supporting the vertical portions of each two adjacent door tracks intermediate the sides of said door opening, a cross track above and substantially in the plane of said door opening and within said building for supporting said removable post for movement laterally of said door opening, and means for suspending said post from said cross track for movement with respect thereto, said means comprising a roller trolley within said cross track and an offset swivel connection between said trolley and the upper end of said post.
- 70 7. In an overhead door construction, a plurality of doors movable from a vertical position to a substantially horizontal overhead position, a pair of tracks for supporting and guiding each of 75 said doors, a removable post between the adjacent edges of said doors and supporting portions of the intermediate tracks, means for supporting said post for movement from door supporting position to a position at one side of the door opening, means for locking said post in door supporting position, and means actuatable by said door post locking means for locking said doors in their overhead positions when said post is unlocked.
8. In an overhead door construction, a plurality 10 of doors positioned side by side in closed position and adapted to close a door opening, a removable post within said door opening and between said doors, a pair of tracks for supporting and guiding the adjacent edges of said doors from a vertical 15 closed position to a substantially horizontal overhead position; each of said tracks having a vertical portion, an overhead horizontal portion, and a curved connecting portion; said tracks being broken adjacent the lower end of said curved portions, the portions of the tracks below the break being carried by said post and the portions of the tracks above the break being fixed, means for supporting said post for movement from post supporting position to an out of the way position, 20 means carried by said post for locking the same in door supporting position, a latch associated with the fixed portions of the tracks for holding the doors in overhead position, and means associated with said post locking means for operating said 25 latch, said latch being automatically moved to latching position when said post locking means is unlocked and said latch being automatically moved out of door holding position when said post locking means is moved to locking position. 30
9. In an overhead door construction, a plurality of doors positioned side by side in closed position and adapted to close a door opening, a removable post within said door opening and between said doors, a pair of tracks for supporting and guiding 35 the adjacent edges of said doors from a vertical closed position to a substantially horizontal overhead position; each of said tracks having a vertical portion, an overhead horizontal portion, and a curved connecting portion; said tracks being 40 broken adjacent the lower end of said curved portions, the portions of the tracks below the break being carried by said post and the portions of the tracks above the break being fixed, means for supporting said post for movement from post supporting position to an out of the way position, 45 means carried by said post for locking the same in door supporting position and including a locking member mounted for reciprocation and an operating member mounted for vertical and rotary movements, a latch associated with the fixed portions of the tracks for holding the doors in overhead position, a key member engageable with said latch when said operating member is vertically moved to lock said locking member, said 50 key member and latch being turned when said operating member is rotated, and means for preventing rotation of said operating member except when said locking member is in locking position and said key member is in latch engaging position. 55
10. In an overhead door construction, a plurality of doors movable from a vertical position to a substantially horizontal overhead position, a pair of tracks for supporting and guiding each of 70 said doors, each track having a horizontal overhead section and a vertical section, a removable post for supporting the vertical sections of certain of said door tracks, a cross track for supporting said post for movement laterally of said door open- 75

ing, a bolt carried by said post for locking the same in door supporting position, a bar carried by said post for rotary and vertical movements and connected to said bolt, a guide for said bar and having a vertical slot and a circumferential slot leading from the upper end of the vertical

slot, an operating member secured to said bar and movable in said slots, a pivoted latch above said post for locking the doors in overhead position and having a key-way, and a key carried by said bar and engageable in said key-way.

DAVID M. ROBINSON.
